UNITED STATES PATENT OFFICE.

PETER J. GAGNON, JR., OF LOWELL, MASSACHUSETTS, ASSIGNOR OF ONE-THIRD TO JOSEPH L. HENDERSON AND ONE-THIRD TO ALBERT J. GAGNON, BOTH OF LOWELL, MASSACHUSETTS.

AUTOMATIC FEED-REGULATING MECHANISM.

Application filed April 10, 1924. Serial No. 705,572.

To all whom it may concern:

Be it known that I, PETER J. GAGNON, Jr., a citizen of the United States, and a resident of Lowell, county of Middlesex, State of Massachusetts, have invented an Improvement in Automatic Feed-Regulating Mechanism, of which the following description, in connection with the accompanying drawing, is a specification, like characters on the drawing representing like parts.

This invention relates to improvements in regulating devices for intermittently operable feeding mechanisms and the object thereof is to provide a novel regulating means for controlling the actuation of the feeding mechanism.

More particularly the invention relates to feeding mechanisms comprising an intermittently rotatable member operated by a pawl and ratchet mechanism and one of the objects of the invention is to provide a novel and improved pawl mechanism in which the pawl controlling means is directly mounted upon the pawl carrier.

A further object of the invention is to provide a novel pawl mechanism which can be readily substituted for the pawl of usual types of machines of this character.

A further object of the invention is to provide a pawl mechanism comprising a reversible pawl thereby adapting the device to rotate the ratchet either in a clockwise or counter-clockwise direction.

These objects are accomplished in the present invention by providing a pawl support in which is mounted a preferably reversible pawl which is controlled by an electro-magnet mounted directly upon the pawl support, the support preferably being of such a character that it can be readily mounted upon the usual pawl carrier of the feeding mechanisms of this general type. The action of the electromagnet may be controlled in any suitable manner as by an automatically operable switch mechanism actuated by mechanical means or by variations in fluid pressure, either above or below atmospheric pressure, or by variations in voltage of an electric circuit, or otherwise.

A further important object of the invention is to provide means for preventing the actuation of the feed regulating means upon

less than a predetermined variation in fluid pressure when the regulating means is automatically controlled by variations in pressure in a passage, the pressure in which varies in correlation to the amount of material delivered to, or from, or consumed by, the machine, for example, in machines having air separators, such as, grinding machines to which the material to be ground is delivered by the feeding mechanism and the ground material removed from the grinding chamber by an air separator.

The present invention is adapted to control the amount of material delivered to the grinding mill in correlation to the variation in fluid pressure in the separating chamber, thereby automatically preventing the delivery of too great an amount of material to the grinding chamber which would prevent proper operation of the grinding mechanism and by such regulation maintaining a uniform suction in the air separator which will insure the delivery of a substantially uniform product. By preventing the actuation of the regulating means upon less than a predetermined variation of fluid pressure in the air separator unnecessary stopping and starting of the feeding mechanism is avoided without interfering with the proper and efficient operation of the mill and wear and tear upon the regulating mechanism reduced to a minimum.

The feed regulating mechanism is adapted to various uses, such, for example, as controlling the feeding mechanism of fuel feeders for heating furnaces or steam boiler furnaces in which the feed regulator may be controlled by variations in air or steam pressure in the passage leading to the furnace, or by variations in the pressure within the furnace itself, or in the flue leading from the furnace, or the feed regulator may be controlled by the variations in steam pressure in the boiler or in pipes leading therefrom, or by variations of the speed of motors actuated by the steam from the boiler.

In short the present invention, in its broad sense, comprises means for automatically controlling the feed regulating mechanism of the pawl and ratchet type upon variations

of condition in the machine or its accessories which are correlated to the amount of material delivered by the feeding mechanism, the operation of the controlling mechanism being so governed as not to actuate the feeding mechanism upon less than a predetermined variation of the condition of the medium which controls the regulator.

10 A preferred embodiment of the present invention is illustrated herein as applied to the regulating mechanism disclosed in my prior Patent No. 1,421,343 granted June 27, 1922, for automatic feed regulator for machines having air separators. It will, however, be understood that the invention described herein is of general utility and is applicable to various other machines and mechanisms within the scope of the claims.

20 In the drawings:

Fig. 1 comprises an elevation of a centrifugal grinding mill of the "Raymond" type illustrating the present invention applied thereto;

25 Fig. 2 is a detail view of a portion of the base of the mill showing the ports through which air is admitted into the mill;

30 Fig. 3 is an enlarged detail view, partly in vertical section, of the novel pawl mechanism embodying the invention in operative relation to the ratchet of the rotary feeding member;

35 Fig. 4 is an enlarged detail side elevation of the mechanism illustrated in Fig. 3; and,

Fig. 5 is an enlarged detail elevation of a portion of the regulating mechanism.

The machine illustrated in the accompanying drawings is a centrifugal grinding mill of the well known "Raymond" type 40 having an air separator and a collector for the finished material. Forms of this general type of grinding mill are illustrated and described in Patent No. 897,400 granted to A. Raymond September 1, 1908.

45 As illustrated in the drawings the mill is supported upon a suitable bed 1 and comprises a frame 2 having a grinding ring 3 which co-operates with a series of centrifugal rollers 4 supported upon shafts (not shown) which are pivotally secured at their upper ends to a spider carried by a vertical shaft having at its lower end a gear which is driven by a bevel gear 5 upon a main driving shaft 6. The grinding ring and 50 co-operating centrifugal rollers are located a short distance above the bottom of the grinding chamber and the material which is fed into the mill drops into the grinding chamber and is thrown upwardly into the path of the rollers by plows which are carried by a sleeve shaft connected to the spider which actuates the centrifugal rollers as disclosed in the prior patent aforesaid.

55 The material is fed into the grinding

chamber by a pocketed rotatable cylinder 65 which is intermittently actuated by pawl and ratchet mechanism.

The air separating chamber in this type of mill is located above and forms a continuation of the grinding chamber. The 70 wall 7 of the air separating chamber extends upwardly from the grinding ring and expands slightly outwardly, thereby being of inverted truncated conical form. The top 8 of the air separator is of conical form and communicates with a central upwardly extending pipe 9 which leads to the eye of a blower 10 which discharges through a pipe 11 tangentially into the cylindrical upper portion 12 of a dust collector of the "cyclone" type having a downwardly extending conical barrel 13 provided at its bottom with a hopper 14 from which the finished material may be discharged. A pipe 15 leads from the center of the top of the cylindrical portion of the collector to a drum 16 which encloses the lower portion of the grinding chamber which extends below the grinding ring. A series of tangential ports, formed by vertical walls 17, lead from the drum 16 to the grinding chamber beneath the grinding ring.

55 The air separating chamber which is enclosed by the wall 7 and top 8 and the pipe 9 leading therefrom to the blower form a conduit through which the air laden with finely ground material is drawn from the grinding chamber.

60 Material is fed into the grinding chamber through a chute or hopper 18 which leads to a pocketed rotatable cylinder which is mounted upon a shaft 19 which is rotated by a ratchet 20. The material delivered by the rotatable pocketed roll drops to the bottom of the grinding chamber. A series of ports, formed by vertical converging walls, lead from the drum 16 to the lower portion of the grinding chamber beneath the grinding ring. Thus the current of air produced by the blower draws the finely ground material from the air separating chamber and delivers it to the collector in which the material is deposited and the air is then delivered from the collector into the drum 16 from which it enters the mill through the 100 tangential ports below the grinding chamber.

65 If, during the operation of the mill, an excessive amount of material is fed into the grinding chamber, the tangential admission ports for the air become more or less filled up and clogged thereby shutting off the free entrance of air into the mill and consequently diminishing the air pressure within the air separator. This seriously modifies the action of the separator and also interferes with the proper functioning of the mill.

70 In usual types of the "Raymond" mills

set forth in Patent No. 897,400 above described means were provided for manually regulating the feeding mechanism for the purpose of correlating the amount of material fed to that which was properly ground in the mill. In my prior Patent No. 1,421,343 automatic means are disclosed for regulating the feeding means operable by variations of the air pressure in the air separator. This was accomplished by providing a pneumatically operated device for controlling the current of a solenoid, the core of which was attached to a reciprocating pawl which engaged the ratchet of the feed roller and which when energized would remove the pawl from engagement with the ratchet of the feed roller.

By the present invention the controlling mechanism disclosed in my prior patent aforesaid is simplified and further improved by the provision of means for preventing actuation of the regulating device unless a predetermined variation in fluid pressure in the air separator is attained. The pawl mechanism is so designed that it may be readily substituted for the usual types of pawl mechanisms employed in mills of this character and also for similar pawl mechanisms of other machines.

The invention in its broader aspect comprises improvements in feed regulating devices and other intermittently operated pawl-actuated mechanisms in which it is desirable to correlate the intermittently actuated device to the demand of the machine or apparatus to or from which the material is delivered or in which it is consumed or otherwise treated by controlling the operation of the feeding mechanism from variations of pressure in a chamber or other conduit, the fluid pressure in which is dependent upon the demand or proper operation of the machine.

The terms "fluid pressure" and "air pressure" are used herein in a broad sense as including pressures either above atmospheric pressure or pressures below atmospheric pressure such as are produced by suction.

In the illustrative embodiment of the invention shown in the drawings, in which the feeding mechanism delivers material to a grinding chamber of a grinding mill, the mechanism for actuating the feeding ratchet 20, which is connected to the shaft of the feed roll, comprises a pawl carrier having arms 22 and 23 located upon opposite sides of the ratchet 20 and pivotally movable about the axis of the shaft 19, the arms 22 and 23 being connected by webs 24 and 25 thereby producing a rigid pawl-carrying frame structure. A shaft 26, also connecting the arms 22 and 23, provides a pivotal support for the pawl, in the usual constructions, which engages the ratchet 20. The arm 23 extends a considerable distance above the

periphery of the ratchet and is provided with a stud shaft 27 which is connected by a link 28 to a crank 29 upon a shaft 30 which is driven in any suitable manner from the actuating mechanism of the machine, as, for example, through a belt pulley 31.

In the construction disclosed in my prior Patent No. 1,421,343 the usual pawl for rotating the ratchet of the pocketed feeding roller is shown as connected by a link to a suitably supported solenoid the circuit of which is controlled by a pneumatically actuated switch mechanism which is operated by variations of pressure in the air separator.

In the present invention the solenoid is mounted directly upon the pawl carrier and in the preferred construction illustrated herein a pawl support is provided which can be readily mounted upon the pawl carrier above described which is employed in the usual "Raymond" type of machine.

The pawl support shown in the accompanying drawings comprises a plate or bar 32 having an aperture 33 to receive the shaft 26 upon which the usual pawl is mounted and is provided at its opposite end with a bifurcated offset extension 34 which embraces the web 24 of the pawl carrier. Thus the pawl support 32 may be readily assembled upon the usual pawl carrier by merely withdrawing the shaft 26, removing the original pawl, then applying the bifurcated end of the pawl support upon the web 24 and reinserting the shaft 26. The pawl support 32 is provided with a vertical slot 35 in which a pawl 36 is slidably mounted and is caused to rest, by the action of gravity, upon the teeth of the ratchet 20. The upper end of the pawl 36 is rigidly connected by a bar 37 of brass, or other nonconductor of magnetic lines of force, to the lower end of the core 38 of a solenoid 39 carried by a frame 40 having standards 41 provided with slotted laterally extending feet 42 which are secured by machine screws or bolts 43 to the upper face of the pawl support 32. The slot 35 in the pawl support desirably is of rectangular cross section and the pawl 36 of corresponding rectangular cross section so that the pawl 36 may be reversed in case the teeth of the ratchet 20 are reversely arranged. Thus the pawl carrier may be readily adapted to any feeding mechanism of the ratchet and pawl type.

The current supplied to the solenoid 39 may be controlled in any suitable manner, either manually or automatically, within the scope of the claims which are addressed to the ratchet-actuating mechanism. In the present embodiment of the invention the solenoid control is effected through a pneumatically actuated device, connected to the air separator, similar to that disclosed in my prior patent aforesaid.

The controlling device illustrated comprises a conical pneumatic chamber 44 which is mounted in the upper end of a suitable box or receptacle 45 which may be secured to the wall of the room or to the mill in any convenient position. The upper end of the pneumatic chamber is connected to the air separator by a conduit 46, preferably having a flexible section 47, such as, a piece of rubber hose, to prevent transmission of the vibration of the mill to the pneumatic chamber. The lower end of the pneumatic chamber 44 is closed by a flexible diaphragm 48 to which is secured a vertical switch rod 49 having a laterally extending contact plate 50, the lower end of the rod 49 being slidably mounted in a bracket 51 mounted upon a suitable insulating plate 52 secured to the wall of the regulator box 20 or receptacle 45. A helical spring 53, connected at one end to the bar 49 and at the other end to a boss 54 upon the bracket 51, tends to hold the switch rod 49 against its bearing in the end of the bracket 51 and thereby prevent vibration of this depending rod.

The current from a suitable generator, which for convenience of illustration is shown as a battery 55, leads to a knife switch 56, one of the terminals 57 of which is connected by a conductor 58 to the contact rod 49. The other terminal 59 of the switch is connected to a conductor 60 which leads to the solenoid 39 and the return conductor 61 from the solenoid leads to a binding post 62 upon an L-shaped spring arm 63 which extends over the contact plate 50 and is provided with an adjustable contact member or screw 64 located immediately above a complementary contact member on the plate 50.

When in the operation of the machine the air pressure in the air separator is diminished by the clogging up of the air admission ports in the lower portion of the grinding chamber the diaphragm 48 of the pneumatic chamber 44 will be raised thereby causing the contact plate 50 to engage the complementary contact member 64 at the end of the spring arm 63 thereby completing the circuit from the switch through the conductor 58, the contact members 50 and 64, the spring arm 63 to the solenoid and thence through the conductor 60 to the other terminal 59 of the switch 56. The solenoid, when energized by the current, will withdraw and withhold the pawl from engagement with the ratchet until the material in the base of the grinding chamber has been sufficiently reduced to admit enough air to increase the air pressure in the separator to a point at which the diaphragm in the pneumatic chamber will be permitted to descend sufficiently to break the contact between the plate 50 and the complementary contact

member 64. When the circuit is thus broken the pawl will drop by the action of gravity into engagement with the teeth of the ratchet 20 and feeding of the material will be resumed.

It has been found by experience that this control may in some instances be too sensitive and will cause unnecessarily frequent actuations of the feeding mechanism. Another object of the invention is to provide means for reducing the sensitiveness of the control. This is accomplished by providing means which will prevent the separation of the contact members 50 and 64 upon less than a predetermined variation of the air pressure in the separating chambers, or in other words, until the amount of suction in the air chamber has been reduced to a predetermined amount. This is accomplished by providing automatically operable means for flexing the spring 63 which carries the contact member 64 in a direction to maintain the contact members in contact until a predetermined condition of air pressure in the separating chamber has been established.

In the illustrative embodiment of the invention disclosed herein a supplementary solenoid 65 is mounted in a suitable bracket 66 upon one of the walls of the box 45 and the core 67 of the solenoid is provided with an aperture having an insulated lining 68 into which projects a spring 69 which is coiled intermediate of its ends upon a boss 70 carried by a bracket 71 which is secured to another wall of the box 45. The opposite end 72 of the spring extends across and normally lightly engages the spring contact member 63 at a sufficient distance from its support to enable it to depress the spring contact member 63 when the solenoid 65 is energized. The solenoid 65 is located in a shunt from the conductors leading to the pawl-actuating solenoid 39.

As illustrated herein the conductor 60 is connected to a binding post 73 mounted in the box 45 and a shunt conductor 74 runs from this binding post to the solenoid 65. A conductor 75 runs from the solenoid 68 to the binding post 62 upon the spring contact member 63. Consequently when the diaphragm 48 is raised by diminution of air pressure sufficiently to cause the contact plate 50 upon the rod 49 to engage the complementary contact member 64 upon the spring contact member 63 a current will not only be passed through the pawl-actuating solenoid 37, but also through the supplementary solenoid 65. The core 67 of the solenoid will then be raised causing the spring 69 to be pivotally moved about its fulcrum 70, thereby causing its end 72 to press down upon the spring contact member 63, thereby forcing the contact member 64 more firmly into engagement with the contact plate 50 and maintaining it in such po-

sition until the contact rod 49 has been lowered by the increase in air pressure in the pneumatic chamber 44 sufficiently to relieve the pressure of the end 72 of the spring

5 69 upon the spring contact member 63, after which the plate 50 will be separated from the contact member 64 and the circuit to the main solenoid broken, thus permitting the pawl again to engage the teeth of the

10 feeding ratchet.

Suitable means, such as set screws 76 and 77, may be provided to adjust the limits of movement of the solenoid core 67, thereby providing an accurate control of the action

15 of the supplemental solenoid and consequently controlling the effective movements of the contact members 50 and 64. By adjusting the position of the adjustable contact member 64 the amount of variation of air

20 pressure in the pneumatic chamber 44 required to make and break the circuits leading to the solenoid may be accurately determined and the actuation of the contact members upon variations of air pressure in 25 the air chamber less than a predetermined amount prevented.

It will be understood that the embodiment of the invention disclosed herein is of an illustrative character and is not restrictive 30 and that various changes in form, construction and arrangement of parts may be made within the spirit and scope of the following claims.

It will also be understood that the invention is adapted to other uses than upon feeding mechanisms to which reference has been made, for example, a screw conveyer leading to a weighing machine and intermittently rotated by pawl and ratchet mechanism may be equipped with the present invention and the actuation of the conveyer arrested by a switch in the electric circuit of the solenoid operable by the scale beam when a predetermined amount of material 45 has been delivered to the scale; the actuation of the feeding mechanism for any motor driven machine may be controlled by a switch actuated when a predetermined variation of voltage is attained. The invention 50 also may be applied to any machine or apparatus having a conduit, chamber or other passage which is subject to variation in fluid pressure dependent upon, or correlated to, the amount of material delivered to or 55 from or consumed within the apparatus or a part of it as will be obvious to those skilled in the art to which such machine or apparatus relates.

Having thus described the invention, what 60 is claimed as new, and desired to be secured by Letters Patent, is:

1. In a machine comprising a rotatable member and means for actuating the same including a ratchet and a co-operating pawl, a reciprocable pawl carrier, an electromag-

net mounted on said pawl carrier for controlling the relation of said pawl to said ratchet, means for supplying an electric current to said electromagnet and means for controlling said current whereby said pawl 70 may be caused to engage, or to be disengaged from, said ratchet.

2. In a machine comprising a rotatable member and means for actuating the same including a ratchet and a co-operating pawl, a reciprocable pawl carrier, an electromagnet mounted on said pawl carrier, a pawl slidably mounted in said pawl carrier normally engaging said ratchet, but movable out of engagement by said electromagnet when the latter is energized, means for supplying an electric current to said electromagnet and means for controlling said current.

3. In a machine comprising a rotatable member and means for actuating the same including a ratchet and a co-operating pawl, a reciprocable pawl carrier, an electromagnet mounted on said pawl carrier, a reversible pawl slidably mounted in said pawl carrier normally engaging said ratchet operable alternatively to engage ratchets provided with reversely arranged teeth, means for supplying an electric current to said magnet to cause the same when energized to remove said pawl from engagement with said ratchet and means for controlling said current.

4. In a machine comprising a rotatable member and means for actuating the same including a ratchet, a co-operating pawl, a solenoid having a core, a non-conductor of magnetic lines of forces connecting said core to said pawl, a reciprocable carrier supporting said solenoid, means for supplying an electric current to said solenoid and means for controlling said current to cause said solenoid when energized to remove said pawl from engagement with said ratchet.

5. In a machine comprising a rotatable member, means for actuating the same intermittently including a ratchet, a reciprocable pawl carrier, a solenoid having a support detachably mounted on said pawl carrier, a pawl slidably mounted in said support and normally engaging said ratchet, a non-conductor of magnetic lines of forces connecting said pawl rigidly to the core of said solenoid, means for supplying an electric current to said solenoid and means for controlling said current to cause said solenoid when energized to remove said pawl from engagement with said ratchet.

6. In a machine comprising a rotatable member and means for actuating the same intermittently including a ratchet, a pawl carrier having arms located on opposite sides of said ratchet, pivotally movable about the axis of said ratchet and having members connecting said arms, an electro-

magnet having a support adapted to be secured to said arm-connecting members, a pawl slidably mounted in said support normally engaging said ratchet, means for supplying an electric current to said electromagnet to cause the same when energized to remove said pawl from said ratchet and means for controlling said electric current.

7. A pawl mechanism for machines having an intermittently actuated rotatable member provided with a ratchet comprising a pawl carrier having arms located upon opposite sides of said ratchet and pivotally movable about the axis of said ratchet and connected by a web and by a shaft spaced apart from said web, a pawl support having means respectively to engage said web and said shaft, a pawl slidably mounted in said support adapted normally to engage said ratchet and an electromagnet mounted upon said pawl support and operable when energized to remove said pawl from engagement with said ratchet.

8. A pawl mechanism for machines having an intermittently actuated rotatable member provided with a ratchet comprising a pawl carrier having arms located upon opposite sides of said ratchet and pivotally movable about the axis of said ratchet and connected by a web and by a shaft spaced apart from said web, a pawl support having means respectively to engage said web and said shaft, a pawl slidably mounted in said support adapted normally to engage said ratchet, a solenoid mounted on said support having a core rigidly connected to said pawl by a non-conductor of magnetic lines of forces whereby said solenoid when energized will remove said pawl from engagement with said ratchet.

9. In a machine of the class described having an intermittently operable rotatable feeding mechanism for supplying material thereto and a passage subject to variations in fluid pressure in response to the demands of the machine, regulating means automatically operable by the variations of fluid pressure from a definite pressure in said passage to control said feeding means and means for preventing actuation of said regulating means upon variations of pressure less than a predetermined amount from said definite pressure.

10. In a machine of the class described having an intermittently operable feeding mechanism for supplying material thereto, means including an electromagnet for controlling said feeding means, a conduit subject to variations in fluid pressure in response to the demands of the machine, a pneumatic chamber communicating with said conduit, a switch in the circuit of said electromagnet operable by variations in pressure in said pneumatic chamber from a definite pressure and means for preventing the actuation of

said switch upon variations of pressure less than a predetermined amount from said definite pressure.

11. In a machine of the class described having an intermittently operable feeding mechanism for supplying material thereto, means including an electromagnet for controlling said feeding means, a conduit subject to variations in fluid pressure in response to the demands of the machine, a pneumatic chamber communicating with said conduit, a switch in the circuit of said electromagnet operable by variations in pressure in said pneumatic chamber from a definite pressure, a shunt from the circuit of said electromagnet, a supplementary electromagnet in said shunt circuit and means operable by said supplementary magnet to prevent actuation of said switch upon variations of pressure less than a predetermined amount from said definite pressure.

12. In a machine of the class described having an intermittently operable feeding mechanism for supplying material thereto, means including an electromagnet for controlling said feeding means, a conduit subject to variations in air pressure in response to the demands of the machine, a pneumatic chamber communicating with said conduit, a switch in the circuit of said electromagnet operable by variations in pressure in said pneumatic chamber from a definite pressure, a shunt from the circuit of said electromagnet, a supplementary electromagnet in said shunt circuit, resilient means operable by said supplementary magnet engaging said switch acting to prevent the operation thereof by variations of pressure less than a predetermined amount from said definite pressure.

13. In a machine of the class described comprising grinding means, rotatable feeding means including a ratchet and a reciprocating pawl for rotating the same and an air separator for removing the finished material, electrically actuated means including an electromagnet adapted when energized to render the action of said pawl ineffective, a switch in the circuit of said electromagnet, means operable by a diminution of the air pressure in said air separator below a definite pressure to cause said switch to complete the circuit of said electromagnet and means for preventing interruption of the completed circuit until said definite pressure in said air separator has been established.

14. In a machine of the class described comprising grinding means, means for feeding the material to be ground to said grinding means, a separating chamber, means for creating a suction of air through said separating chamber to remove the finely ground material therefrom, means for regulating said feeding means operable by variations of the partial vacuum in said separating

chamber from a definite pressure and means for preventing actuation of said regulating means by variations in air pressure in said separating chamber less than a predetermined amount from said definite pressure.

15. In a machine of the class described comprising feeding means, a separating chamber and means for creating a suction of air through said separating chamber to remove the finely ground material therefrom, regulating means for arresting the feeding

of the material to the machine operable by the diminution of the air pressure in said air chamber below a definite pressure and means for preventing the actuation of said regulating means upon less than a predetermined amount of diminution of air pressure below said definite pressure.

In testimony whereof, I have signed my name to this specification.

PETER J. GAGNON, JR.
